SLACK OR CUTTINGS REMOVING DEVICE FOR KERF-CUTTING MACHINES

William T. McCullough, Chicago, Ill., assignor to Goodman Manufacturing Company, Chicago, Ill., a corporation of Illinois

Application October 21, 1943, Serial No. 507,064

7 Claims. (Cl. 262—30)

This invention relates to improvements in slack or cuttings removing devices for kerf-cutting machines, and more particularly to cuttings removable devices of the screw or helical conveyor type similar to those illustrated in my prior Patent No. 2,320,004, filed December 6, 1941, and my prior application Serial No. 464,594, filed November 5, 1942.

Among the objects of the present invention is to provide an improved form and arrangement of rotatable sweep or impeller device to insure the positive feeding of the cuttings into the screw conveyor.

A further object of my invention is to provide an improved construction for detachably mounting the cuttings removal device on the machine, to permit ready removal for repair or replacement of said device.

A still further object of my invention is to provide an interlocking connection between the screw conveyor control clutch and the fastening device.

The invention may best be understood by reference to the accompanying drawings, in which:

Figure 1 is a fragmentary plan view of the rear end of a kerf-cutting machine with a slack-removing device constructed in accordance with my invention attached thereto and shown in part in horizontal section;

Figure 2 is a rear view of the machine, drawn to an enlarged scale, with parts of the slack-removing device shown in section;

Figure 3 is a fragmentary view in side elevation of the rear part of the machine, with certain parts of the machine and the slack-removing device shown in substantially longitudinal section;

Figure 4 is a partial fragmentary sectional view taken substantially along lines 4—4 of Figure 1;

Figure 5 is a fragmentary plan view of the rear end of the machine, drawn to the same scale as Figure 1, with the slack-removing device attached thereto; and

Figure 6 is a fragmentary transverse sectional view showing certain details of the cuttings sweep and the means for deflecting the cuttings onto the slack-removing conveyor.

Referring now to the details of construction of the embodiment of my invention illustrated in the drawings, the slack-removing device is, in the main, of a construction and arrangement similar to that disclosed in my prior patent and application previously referred to, so the principal parts thereof may be described more or less generally, excepting as to those features which

will be more particularly set forth as forming the subject matter of the present invention.

The slack-removing device is shown as applied to a kerf-cutting machine of conventional room and pillar type, including a main frame 11 having a cutter bar 12 projecting forwardly therefrom. As usual, a cutter chain 13 is driven orbitally about said cutter bar and operates in a cuttings channel defined by side walls 15, 15 and a base plate 16 beneath a drive motor 14. The cutter chain is driven by a sprocket 17 driven as usual from the motor 14 so as to bring the cuttings rearwardly through the cuttings channel for discharge at the rear end of the machine.

15 The slack-removing device includes a tubular casing 20 with a screw conveyor element 21 therein, disposed transversely across the cuttings channel at the rear end of the machine. Said tubular casing has an elongated cuttings receiving aperture 22 on its inner side opposite and closely adjacent the cutter chain sprocket 17. Said casing is arranged to close the rear end of the cuttings channel so that substantially all of the cuttings brought back by the cutter chain will be received and be discharged by the slack-removing device.

20 In order to insure the positive feed of cuttings through the aperture 22 and into the conveyor casing 20, I have heretofore disclosed, in my application Serial No. 464,594, a rotary sweep or agitator having radially disposed arms secured to the bottom of the cutter chain sprocket. In carrying out the present invention I provide an improved form of sweep 23 wherein a plurality of impeller arms are disposed at a substantial retreating angle relative to the normal direction of rotation of the sweep, so as to provide a more positive propelling action for feeding the cuttings to the screw conveyor. In the form of sweep shown herein, a hub 25 of said sweep is suitably 25 secured to the lower end of the cutter chain sprocket 11, as by nut 26, and four arms 27, 27 extend substantially tangentially of said hub. The sweep is designed for normal rotation in a counterclockwise direction, as seen in Figure 1, and each of the arms 27, 27 moves in a counterclockwise direction at a substantial retreating angle to the direction of rotation of the sweep herein about ninety degrees to the radial lines of said sweep.

30 The arms 27 are each formed of a horizontal web 28 adapted to sweep the bottom plate 16, and an upright impeller face 29 along its forward edge. The outer ends of said arms move in a path approaching the screw conveyor element 21 quite closely, in the form shown said path ex-

tending well into the aperture 22 of the casing 20, as shown in Figure 1.

I also mount an upright arcuate baffle plate or deflector 30 within the cuttings passage, to fill the corner space between the left-hand side wall 15 and the rear end of said cuttings passage, as seen in Figure 1. The baffle plate 30 may be held in place by a bolt 31 passing through the front end thereof, and a second bolt 32 passing through the leg of an L-shaped horizontally disposed bracket 33 having its outer end secured to the baffle plate adjacent its rear end, as by welding. The rear end of said baffle plate terminates at the left or advance side of the cuttings receiving aperture 22 of the casing 20.

A baffle plate 24 is secured as by welding at its rear end to the casing 20 adjacent the outer end of the opening 22, and projects forwardly and inwardly toward the sweep 23, as shown in Figure 1. A flexible extension 240, made of rubber or similar material, is fixed on the end of said baffle plate so as to be projected into the path of the arms 27, 27 and assist in directing the cuttings into the opening 22.

With the arrangement of parts thus described, the cuttings brought back by the cutter chain, which otherwise would collect on the base plate 16 and pile up in the rear left-hand corner of the discharge passage, are positively engaged by the rearwardly inclined sweep arms 27, so as to tend to force them radially outwardly toward the arcuate baffle plate 30 while sweeping them rearwardly. As each arm 27 approaches the aperture 22 of the casing, the cuttings are positively forced rearwardly through said aperture 22 and into the path of the screw conveyer 21. Thus, the cuttings are constantly being swept along the base plate 16 of the discharge passage, and fed into the conveyer, so that clogging of the discharge passage due to the accumulation of inert masses of cuttings therein is entirely overcome.

The screw conveyer element 21 consists of a blade 211 fixed on a tubular shaft 212, driven by power by the cutting machine motor 14, through suitable gearing which herein includes a drive shaft 34 journaled in spaced anti-friction bearing members 35, 36 in a housing 37, which encloses one end of the casing 20. The drive shaft 34 has a bevel gear 38 keyed on its outer end, meshed with a bevel pinion 39 rotatably mounted on a sprocket shaft 40 extending transversely of the shaft 34. Said sprocket shaft is journaled in spaced anti-friction bearings 41 and 42 at front and rear, respectively, of the housing 37. A sliding clutch collar 43 is feathered on shaft 40 within said housing, and has clutch teeth 44 for engaging corresponding clutch teeth 46 formed on the inner face of bevel pinion 39. The clutch collar 43 is shifted by a yoke 45 fixed on a rocking shaft 48, which extends upwardly through the outer end of housing 37, and has a control lever 47 mounted on its upper end.

The sprocket shaft 40 extends forwardly of the casing 37 and has a drive sprocket 50 thereon, adapted for engagement by a chain 51 which extends to a sprocket 52 fixed on a shaft 53 extending from the rear end of the kerf-cutting machine. In the form shown the shaft 53 is part of the truck driving connection commonly used on mining machines of this character, driven as usual from the motor 14 through gearing which need not be further described herein, as it forms no part of the present invention.

The drive sprocket 50 is preferably connected

to shaft 40 through an automatic limit clutch device, herein consisting of clutch members 55 and 56 having engaging teeth with inclined faces. The clutch member 55 is fixed to the sprocket 50, and the other clutch member 56 is feathered on the shaft 40 and normally urged toward clutch member 55 by a coil spring 54, having its front end seated in a collar 58 fixed on the front end of said shaft. The tension of the coil spring 54 is such as to permit the teeth of clutch members 55 and 56 to become automatically disengaged under a predetermined driving load so as to avoid danger of breakage of the conveyer blade, as, for instance, when excessively large pieces of material become engaged in the screw conveyer.

The tubular casing 20 surrounding the screw conveyer element 21 is provided with an opening 200 along its upper rear side, normally enclosed by a door 57 hinged along its bottom edge so as to afford access to the screw conveyer when necessary for the removal of undesirable pieces of material which may become lodged therein so as to interfere with its proper functioning. In the form shown herein, the hinged door 57 is provided with a locking lug 570 at one end thereof, which is adapted for endwise sliding engagement by a locking pin 63. Said locking pin is guided in spaced ears 630, 630 on the casing 20, and has interlocking operative connection with the clutch control lever 47 in the gear housing 37, through a link 59, which is pivoted at one end to the outer end of said pin and at the other end to the control lever 47. The arrangement is such that the locking pin 63 cannot be shifted to unlock the door 57 without simultaneously disengaging the clutch collar 43 and thus stopping the operation of the screw conveyer.

The slack-removing device has means for attachment or detachment relative to the mining machine frame, herein comprising two brackets 60 and 61 adapted for detachable connection along the outer faces of the two side walls 15, 15 of the cuttings discharge passage. The bracket 60 at the left side of the machine consists of an elongated plate 62 detachably secured at its front end to the adjacent side wall 15, and having its widened rear end projecting rearwardly beyond said wall and terminating in a transversely disposed tubular portion 64, which surrounds the housing 37, which, for convenience, is also tubular in cross section at this point. The tubular portion 64 is preferably formed with a detachable rear half portion 65 split from the front half portion 66 at an upwardly and forwardly inclined angle. Said half portions are joined by bolts 67, 67.

The bracket 61 for the right side of the machine is similar in form to bracket 60 just described above, excepting that its split tubular portion 64 is somewhat larger than the corresponding portion of bracket 60, so as to fit around the large tubular casing 20 adjacent the right end of the slack conveying device.

The brackets 60 and 61 are connected to their respective side walls 15 by a plurality of bolts. In the form shown the left bracket 60 is secured by the same through-bolts 31 and 32, which are employed to secure the baffle plate 30 at the inside of the left side wall 15, as previously described. The bracket 61 is secured to the right side wall 15 by spaced bolts 68 and 69.

While I have herein shown and described one form in which my invention may be embodied, it will be understood that the construction thereof and the arrangement of the various parts may

be altered without departing from the spirit and scope thereof. Furthermore, I do not wish to be construed as limiting my invention to the specific embodiment illustrated, excepting as it may be limited in the appended claims.

I claim as my invention:

1. In a kerf-cutting machine having a frame, a horizontally disposed chain carrying cutter bar having a portion extending through a cuttings discharge passage in said frame, and a drive sprocket for said cutter chain adjacent a horizontally opening outlet for said cuttings discharge passage, the combination of a rotary sweep element mounted in said passage substantially concentric with and below said drive sprocket, said sweep element having a plurality of arms extending at a retreating angle relative to the normal direction of rotation of said drive sprocket, and means for rotating said sweep element in the same direction as said drive sprocket so as to force the cuttings radially outward and through said cuttings outlet.

2. In a kerf-cutting machine having a frame, a chain carrying cutter bar having a portion extending through a cuttings discharge passage in said frame, a cutter chain drive sprocket disposed adjacent the rear end of said passage, a cuttings discharge device including a horizontally disposed casing having an inlet opening in cuttings-receiving relation at the rear end of said passage and having a screw conveyer element therein, a rotary sweep element mounted in said passage substantially concentric with and below said drive sprocket, said sweep element having a plurality of arms extending at a retreating angle to the normal direction of rotation of said sprocket, and means for rotating said sweep element in the same direction as said sprocket so as to force the cuttings radially outward and feed them into the screw element in said casing.

3. In a kerf-cutting machine having a frame, a chain carrying cutter bar having a portion extending through a cuttings discharge passage in said frame, a cutter chain drive sprocket disposed adjacent the rear end of said passage, a cuttings discharge device including a horizontally disposed casing having an inlet opening in cuttings-receiving relation at the rear end of said passage and having a screw conveyer element therein, a rotary sweep element mounted on said drive sprocket below said chain, said sweep element having a plurality of arms extending at a retreating angle to the normal direction of rotation of said sprocket, so as to force the cuttings radially outward and feed them into the screw element in said casing.

4. In a kerf-cutting machine having a frame, a chain carrying cutter bar having a portion extending through a cuttings discharge passage in said frame, a cutter chain drive sprocket disposed adjacent the rear end of said passage, a cuttings

discharge device including a horizontally disposed casing having an inlet opening in cuttings-receiving relation at the rear end of said passage and having a screw conveyer element therein, a rotary sweep element mounted in said passage substantially concentric with and below said drive sprocket, said sweep element having a plurality of arms extending at a retreating angle to the normal direction of rotation of said sprocket, arcuate baffle means in said passage in close confining relation to said sweep arms and terminating at the advance side of the inlet opening of said conveyer casing, and means for rotating said sweep element in the same direction as said sprocket so as to force the cuttings radially outward and feed them into the screw element in said casing.

5. In a kerf-cutting machine having a frame with opposed parallel side walls forming a cuttings discharge passage, a cuttings discharge device including an elongated casing adapted to be disposed horizontally in cuttings receiving relation at the rear end of said cuttings passage, and supporting means for said casing including plates secured along the opposite outer sides of the side walls of said passage and terminating in split straps adapted to extend around said casing and secure said casing to said side walls.

6. In a cuttings discharge device for kerf-cutting machines, an elongated casing having a screw conveyer element rotatably mounted therein, drive means for said screw conveyer at one end of said casing including a clutch and a manual control lever for engaging or disengaging said clutch, said casing also having a removable wall portion to afford access to the screw conveyer element therein, locking means for said removable wall portion on said casing, and means operatively interconnecting said locking means with the manual control lever of said clutch so that said clutch is automatically disengaged whenever said locking means is unlocked to permit said removable wall portion to be opened.

7. In a cuttings discharge device for kerf-cutting machines, an elongated casing having a screw conveyer element rotatably mounted therein, drive means for said screw conveyer at one end of said casing including a clutch and a manual control lever for engaging or disengaging said clutch, said casing also having a removable wall portion hinged to said casing to afford access to the screw conveyer element therein, locking means for said wall portion on said casing including a sliding locking pin and means operatively interconnecting said locking pin with the manual control lever of said clutch so that said clutch is automatically disengaged whenever said locking pin is unlocked to permit said removable wall portion to be opened.
